ELECTRIC DISCONNECT SWITCH

Walter Kowalski, South Milwaukee, Wis., assignor to McGraw-Edison Company, Milwaukee, Wis., a corporation of Delaware

Filed May 25, 1961, Ser. No. 112,561
6 Claims. (Cl. 200—48)

This invention relates to electric switches and, more particularly, to hook stick operated air break disconnect switches.

In the servicing of certain high voltage electrical apparatus such as circuit breakers, the preferred safety practice is to disconnect the apparatus from the energy source by means of a visible air gap device such as a disconnect switch so that it may be visually determined that the device is de-energized and that servicing may proceed in safety. Such disconnect switches are generally mounted in an overhead location and include costly operating mechanisms so that they may be operated from ground level. Prior art hook stick operated disconnect switches were not employed in such installations because their method of operation would require the operator to be located above and to the rear of the switch blade.

It is an object of the invention to provide a hook stick operated disconnect switch which may be operated from below when it is mounted in a horizontal position.

Another object of the invention is to provide a hook stick operated disconnect switch which is latched in each of its opened and closed positions.

Another object of the invention is to provide a disconnect switch having angularly adjustable stationary contacts which allows the supporting structure of the switch blade and the stationary contacts to be located in different planes.

These and other objects and advantages of the instant invention will become more apparent from a detailed description of the preferred embodiment thereof taken with the accompanying drawings in which:

FIG. 1 shows a hook stick operated disconnect switch according to a preferred embodiment of the instant invention employed with electrical apparatus being energized from a bus bar system;

FIG. 2 is a side elevational view of the device shown in FIG. 1;

FIGS. 3 and 4 illustrate the mechanism for latching the switch blade in its open position; and

FIG. 5 shows the stationary contact assembly and means for its angular adjustment and the latch assembly for holding the switch blade in its closed position.

In general terms, the invention comprises a horizontally mounted disconnect switch having an operating lever pivotally mounted intermediate the ends of the switch blade and disposed in a substantially vertical direction, linkage means interconnecting the upper end of the operating lever and a latching member normally holding the switch blade in its connected position so that the application of a force to the lower end of the operating lever by means of a hook stick or the like will move the latching member out of engagement with the switch blade and allow the blade to be pivoted to its disconnected position.

According to a more specific aspect of the invention, a second latching means is disposed at the hinged ends of the switch blade and is adapted to latch the switch blade in its disconnected position. A second linkage means also interconnects the upper end of the operating lever to the second latching means so that pivotal movement of the operating lever under the influence of a hook stick will release the second latching means and allow the switch blade to be rotated to its connected position.

Referring now to the drawings in greater detail, FIGS. 1 and 2 show a hook stick operated air disconnect switch

2

incorporating the instant invention and designated generally by the reference numeral 10. The switch 10 is illustrated connecting an electrical device 11, such as a circuit breaker, to a supply bus 39. The switch 10 includes a first terminal member 12 for pivotally supporting a switch blade 16 and which is shown in the illustrated application to be electrically connected to the bus bar 39 and mounted atop a bus bar support insulator 13. A second terminal member 14 is mounted atop one of the bushings 15 of the device 11 and supports a stationary contact assembly 18.

As seen more specifically in FIGS. 3 and 4, the terminal 14 carries a U-shaped hinge member 20 having spaced vertical legs 21. A hinge clamp 23 is releasably affixed to the hinge end of the blade 16 by bolts 27 and nuts 29 and has a pair of depending arms 24 for pivotal connection to the legs 21 by hinge pins 26 which extend through aligned openings in each. The pins 26 each engage a boss 25 integral with its corresponding arm 24 and each is held in place by a nut 28 received on its threaded end. An arm 30, extending laterally from the clamp 23, receives one end of a coiled counterbalance spring 31 whose other end is affixed to the hinge member 20 through an arm 32 integral with an adjusting wheel 33 which is held between one of the nuts 28 and the member 20.

The stationary contact structure 18, which is shown in greater detail in FIG. 5, comprises pairs of laterally spaced contact fingers 34 secured at their lower ends to the terminal 14 for receiving therebetween the free end of the switch blade 16 in very high pressure electrical engagement. To enhance contact pressure between the contact fingers 34 and the switch blade 16, leaf springs 35 are disposed against the outer surface of each of the contact fingers 24 and are loaded by retaining pins 36 carried by a tie bar 38 extending laterally through the fingers 34 and the springs 35. It can be seen that the reaction between the retaining pins 36 and the springs 35 will hold the contact fingers 34 in high pressure engagement with the end of the switch blade 16 when the latter is in its closed position shown in FIGS. 2 and 5.

Referring specifically now to FIG. 5, the bushing 15 includes a conductive stud 42 extending from its upper end and upon which is mounted an adapter assembly 44 for supporting the terminal 14. The adapter 44 includes a U-shaped base member 45 affixed by nuts 46 to the conductive stud 42 and having a pair of vertical arm portions 48. In addition, the adapter 44 includes a mounting member 49 which is also substantially U-shaped and has a pair of depending leg portions 50 which slidably engage the outer surface of the arms 48. A pair of bolts 51, secured by nuts 52 (only one of which is seen in FIG. 5), extend through aligned apertures in each pair of adjacent portions 48 and 50 on each side of assembly to pivotally support the mounting member 49 on the base member 45. A pair of arc-shaped apertures 54 are formed in each of the legs of the mounting member 50 equidistantly from the axis of the bolts 51 and extending in a generally vertical direction. In addition, a pair of similar arc-shaped apertures 55 are formed in each of the arms of the base of member 45 and each are in register with the corresponding apertures 54 in the legs 50 when the members 45 and 49 are substantially parallel. The center of curvature of each of the apertures 54 and 55 is coincident with the axis of bolts 51 so that relative rotation of members 45 and 49 will move said apertures in parallel circular paths. A bolt 56 extends through each pair of corresponding apertures 54 and 55 and each is secured by a nut 56 which engages the inner surface of arms 48 to provide a good mechanical and electrical connection between the members 45 and 49. Because the apertures 54 and 55 have the same radius of curvature

and are equidistant from the bolts 51, member 49 can be rotated through a plurality of angular positions relative to the base member 45 and may be secured in any of these positions by means of the nuts 54. As seen in FIG. 1, therefore, alignment between the switch blade 16 and the stationary contact assembly 18 can be achieved even though the terminal member 12 is a substantial vertical distance above or below the terminal member 14. Also, as seen in FIG. 5, the adapter assembly 44 allows the switch blade 16 to properly engage each of the contact fingers 34 regardless of the angle it makes with the stud 42.

It will be appreciated that if the stationary contact assembly 18 is displaced vertically relative to the terminal member 12, as seen in FIG. 1, for example, the length of the switch blade 16 will have to be increased if it is to mate properly with said contact assembly. The effective length of the switch blade may be modified for this purpose by loosening the bolts 27 which secure the clamp 23. The blade 16 is then moved inwardly or outwardly relative to the terminal 12 and the clamp 23 is resecured.

As illustrated in FIGS. 1, 2 and 5, a latching assembly 60 is provided for securing the switch blade 16 in its connected position relative to the stationary contact 18. The assembly 60 includes a pair of parallel latch arms 61 (only one of which can be seen in FIG. 5) pivotally mounted on a pin 62 extending between the arms of a U-shaped bracket 63 affixed to the terminal 14. A sear spring 66 surrounds pivot pin 62 and engages the terminal 14 and the latch arms 61 thereby urging said arms for clockwise rotation, as viewed in FIG. 5, into engagement with a latch pin 67 extending laterally through the tip of the switch blade 16. This latching engagement between the latch arms 61 and the pin 67 prevents unintended movement of the switch blade 16 out of its connected position due to the magnetic forces of short circuit currents and the like.

A latch release lever 68 is pivotally mounted near its lower end on the latch pin 67 and has a pair of latch release projections 69 on its lower end which engage the arms 61. An operating handle 70 is shown in FIG. 2 to be pivotally mounted intermediate its ends on the switch blade 16 at a point 71 between the terminals 12 and 14. A pair of parallel links 72 are pivotally connected at 73 to the upper end of latch release arm 68 and at 74 to the upper end of the operating handle 70. It can be seen, therefore, that rotation of the operating handle 70 through a slight counterclockwise angle, by means of a hook stick inserted into the pull ring 75, will rock the latch release lever 68 clockwise from its full position in FIG. 5 to its position shown by phantom lines wherein the latch release projections 69 will engage the latch arms 62 and rotate them counterclockwise to their phantom position against the influence of spring 66. As a result, the latch arm 62 will move out of latching engagement with the pin 67 so that switch blade 16 will be free for pivotal movement to its open position. Rotation of the latch release lever 68 is limited by a pin 64 extending through the tip of switch blade 16 adjacent the latch pin 67 and which lies in the path of the opposite sides of an arcuate slot 65 in the edge of the lever 68.

When the switch blade 16 reaches its fully opened position, a lug 76 extending integrally from the boss 25 (as seen in FIGS. 2 and 3) engages an adjustable stop 77 threadably received in a T-shaped bracket 78 which is secured to the hinge member 20 by mounting bolts 79 which also hold said hinge member to the terminal 12. In addition, the switch blade 16 is held in this position against accidental reclosing due to vibrations, jarring or the like by a latch assembly 81. The latch assembly 81 is similar to the assembly 60 which latches the blade 16 in its closed position and includes a latch pin 82 extending transversely between lugs 83 integral with the legs 24 of clamp 23. Pin 82 is engageable by a pair of latching arms 84 identical to the latch arms 62 and which are urged

by a sear spring 85 for rotation in a counterclockwise direction about a pivot pin 86 extending between the arms of a U-shaped bracket member 87 mounted between the legs 21 of the hinge member 20.

5 A bifurcated latch release lever 88 is rockably mounted on the pin 86 and carries a pair of projecting latch engaging portions 90 adjacent each of the latch arms 84. The other end of the latch release lever 88 is pivotally connected at 91 to a pair of link members 92 whose other ends are pivotally connected through an adjusting link 94 to the operating lever 70 at 74.

10 The link 94 has a slot 95 for adjustable connection to the end of the links 92 by a bolt and nut 96. This allows the effective distance between the points 74 and 91 to be 15 changed to correspond to changes in the effective length of the switch blade 16 as discussed hereinabove.

When the switch is latched in its open position shown by the phantom lines in FIG. 1, release of the latch assembly 81 is accomplished by rotating the operating handle 70 in a counterclockwise direction. As shown in 20 FIG. 4, this moves the link 92 and the latch release lever 88 from their full position to their phantom position whereupon the latch release projections 90 will engage the latch arms 84 to rotate them out of latching engagement 25 with the pin 82. As a result, the switch blade 16 is free for counterclockwise rotation from its phantom position as viewed in FIG. 1 to its connected position shown by full lines.

It can be seen from the foregoing that the invention 30 provides for use with encased electrical apparatus, such as circuit breakers, a disconnect switch which is operable by means of a hook stick from ground level thereby eliminating expensive operating mechanisms required by prior art installations wherein rotating insulator type disconnect 35 switches were employed. In addition, the invention provides an air disconnect switch wherein the circuit breaker bushing and bus bar structure may be employed for supporting the fixed contacts and switch blade respectively thereby eliminating costly switch supporting structure. 40 This is possible because the air break switch is hook stick operated thereby eliminating the necessity for rotating insulator support structure.

While only a single embodiment of the instant invention has been shown and described, it is not intended that 45 the invention be limited thereby, but only by the scope of the appended claims.

I claim:

1. In an electric switch, a pair of terminals having a generally horizontal spaced relation, stationary contact means mounted on one of said terminals, a switch blade 50 mounted on the other of said terminals and pivotal in one direction out of engagement with said stationary contact means, latch means mounted adjacent said stationary contact means and having a member pivotally mounted for movement into and out of latching engagement with said switch blade when the latter is in its connected position, an operating lever pivotally mounted intermediate its ends on said switch blade and extending in a substantially vertical direction and having hook engaging means 55 at its lower end, link means coupling the upper portion of said lever to said member, pivotal movement of said lever in said one direction being operative to move said member out of latching engagement with said switch blade and to pivot said switch blade to its disengaged position, pivotal movement of said lever in an opposite direction being operative to pivot said switchblade into engagement with said stationary contact means and to pivot said member into latching engagement with said switchblade.

2. In an electric switch, a pair of terminals having a generally horizontal spaced relation, stationary contact means mounted on one of said terminals, a switch blade 70 mounted on the other of said terminals and pivotal in one direction out of engagement with respect to said stationary contact means, a latch member pivotally mounted

adjacent said stationary contact means and resiliently urged into latching engagement with said switch blade when the latter is in its connected position, a latch release arm pivotally mounted adjacent said latch member and operable upon pivotal movement in a first direction to move said latch member away from said switch blade, an operating lever pivotally mounted intermediate its ends on said switch blade and extending substantially vertically and having hook engaging means at its lower end, and link means connecting said operating lever to said latch release arm, pivotal movement of said operating lever in said one direction being operative to pivot said latch release arm in said first direction and to pivot said switchblade in said one direction out of engagement with said stationary contact means and into a nominally vertical position, pivotal movement of said operating lever in an opposite direction being operative to pivot said switchblade into engagement with said stationary contact means and to release said latch member for pivotal movement into latching engagement with said switchblade.

3. In an electric switch, a pair of terminals having a generally horizontal spaced relation, stationary contact means mounted on one of said terminals, a switch blade mounted on the other of said terminals and pivotal in one direction out of a connected position and into a nominally vertical disconnected position with respect to said stationary contact means, a first latch means mounted adjacent said stationary contact means for holding said switch blade in its connected position, a second latch means on the other of said terminals for holding said switch blade in its disconnected position, an operating lever pivotally mounted intermediate its ends on said switch blade and extending transversely thereto for pivoting said switch blade between its connected and disconnected positions, and link means connecting said lever and each of said first and second latch means so that the swiveling of said lever will move said first and second latch means in a switch blade releasing direction.

4. In an electric switch, a pair of terminals having a generally horizontal spaced relation, stationary contact means mounted on one of said terminals, a switch blade mounted on the other of said terminals and pivotal into and out of connected and disconnected positions with respect to said stationary contact means, a first latch member pivotally mounted adjacent said stationary contact means and resiliently urged into latching engagement with said switch blade when the latter is in its connected position, a first latch release arm pivotally mounted adjacent said latch member and operable to move said latch member away from said switch blade, a second latch member pivotally mounted on the other of said terminals and resiliently urged into latching engagement with said switch blade when the latter is in its disconnected position, a second latch release arm pivotally mounted adjacent said second latch member and operable to move said second latch member away from said switch blade, an operating lever pivotally mounted intermediate its ends

on said switch blade and extending transversely thereto for moving said switch blade to its disconnected position, and link means connecting said operating lever to said first and second latch release arms, whereby said switch blade may be unlatched and moved into and out of its connected position by the application of a force to the lower end of said operating lever.

5. In an electric switch having a pair of generally horizontally spaced terminals, stationary contact means mounted on one of said terminals, a switch blade mounted on the other of said terminals and pivotal in one direction out of engagement with said stationary contact means and into a nominally vertical disengaged position, first latch means for holding said switch blade in its engaged position and second latch means for holding said switchblade in its disengaged position, operating means pivotally mounted on said switch blade and extending generally downward therefrom, and link means coupling said operating means to said latch means, pivotal movement of said operating means in said one direction being operative to unlatch said first latch means and to move said switch blade to its disengaged position and to latch said second latch means, pivotal movement of said operating member in an opposite direction being operative to unlatch said second latch means and pivot said switchblade into engagement with said stationary contact means and to latch said first latch means.

6. In an electric switch having a pair of generally horizontally spaced terminals, stationary contact means mounted on one of said terminals, a switch blade mounted on the other of said terminals and pivotal out of engagement with said stationary contact means and into a nominally vertical disengaged position, first latch means mounted adjacent said fixed contact means for holding said switch blade in its connected position and second latch means mounted on the other of said terminals for holding said switchblade in its disengaged position, an operating lever pivotally mounted on said switch blade intermediate its ends and extending transversely thereto in a generally vertical direction and having hook engaging means at its lower end, and link means interconnecting the upper portion of said lever and each of said latch means, pivotal movement of said operating lever in a first direction unlatching said first latch means and pivoting said switchblade to its disconnected position and latching said second latch means, pivotal movement of said operating lever in an opposite direction unlatching said second latch means pivoting said switchblade into engagement with said stationary contact means and latching said first latch means.
